(57) **CLAIM**

I claim ornamental design for a hydraulic reversible plate compactor, as shown and described.

DESCRIPTION

FIG. 1 is a front view of a hydraulic reversible plate compactor showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a right side perspective view thereof;

FIG. 8 is a right side view thereof shown in use condition; and,

FIG. 9 is a right rear perspective view thereof shown in folded condition.
